UNITED STATES PATENT OFFICE.

FORREST E. HOWES, OF MATTAPAN, MASSACHUSETTS.

SOUND-TRANSMITTER.

1,008,340.

Specification of Letters Patent. Patented Nov. 14, 1911.

Application filed March 10, 1909. Serial No. 482,482.

To all whom it may concern:

Be it known that I, FORREST E. HOWES, a citizen of the United States, residing at Mattapan, in the county of Suffolk and

5 State of Massachusetts, have invented an Improvement in Sound-Transmitters; of which the following description, in connection with the accompanying drawings, is a specification, like letters on the drawings 10 representing like parts.

This invention relates to mechanism for transmitting sound vibrations transferred from a sound signal station through water, as for example from one ship to another. It is apparent, however, that my invention in certain aspects thereof may be used in other relations.

In order that the principles of the invention may readily be understood, I have disclosed an illustrative embodiment thereof in the accompanying drawing, wherein—

Figure 1 is a horizontal section taken through a portion of a ship and a transmitter embodying my invention; Fig. 2 is 25 a side elevation of the construction shown in Fig. 1 looking toward the left in said figure and the skin of the ship being removed; Fig. 3 is a vertical section showing the adaptation of my invention to boats 30 wherein water is carried as ballast; and Fig. 4 is an enlarged partial view of the structure shown in Fig. 3.

Instruments have heretofore been devised to receive sound vibrations transferred from 35 a sound signaling station through water. So far as I am aware, it has been customary in utilizing such instruments upon ship board to suspend the instrument in a tank within the ship containing water through 40 which and the water surrounding the ship the sound is received from some signaling station. The sound as received in transferred by a suitable microphone or other instrument to the pilot house or other suitable 45 part of the vessel, thus conveying information by which the position of the ship may be ascertained. The employment of tanks or receptacles for receiving such transmitting instruments renders their use expensive and much space is required upon 50 ship board. In accordance with my invention I secure the transmitter against the wall or skin of the ship and preferably the inner face thereof in any suitable manner. I have 55 ascertained that by interposing a suitable transmitting medium between the ship wall

and the vibrator diaphragm of the transmitter, sounds can readily be received by the transmitter and conveyed to the receiving station upon the ship.

Referring more particularly to the drawing, the side or skin of the ship is represented at 1 in Fig. 1. Two of the usual ribs are represented at 2—2, they being here shown as provided with angle irons 3—3 secured by rivets 4—4. Against the wall 1 of the ship, I secure the sound transmitter in any suitable manner. While the transmitter may be of any suitable construction, it is provided with a vibrating diaphragm 5 tuned to approximate the pitch of the sound to be received. Between the diaphragm and the ship's side or skin I interpose a suitable sound transmitting medium preferably secured to the diaphragm or 75 other part of the transmitter in such manner that the instrument is complete in itself and can be readily secured in position. While the medium may be a liquid or a semi-liquid received within a suitable jacket or cap secured to the transmitter, I have herein represented the medium as composed of a layer or sheet 5' of pure, soft gum rubber vulcanized onto the vibrating diaphragm 5. I have ascertained by experiments that rubber 80 will transmit high period vibrations and that it will muffle low period vibrations and that therefore the internal noise of the ship will be muffled to a very considerable extent. The rubber may be of any suitable thickness. 90 Within the scope of my invention other suitable media of a solid nature may be employed. The layer or sheet 5' is thus a sound damping substance.

The diaphragm 5 is provided with a suitable telephonic or microphonic button 7 acted upon by the sound vibrations and serving to convey the resulting electrical impulses by the conductor 8 to the pilot house or other part of the vessel.

The instrument may be secured in position, and preferably removably in any suitable manner. For example, it may be provided with a cap 9 shouldered circumferentially represented at 10 to engage the edge of the diaphragm 5, the cap being threaded and receiving thereon an internally threaded ring 11 overlying the opposite edge of the diaphragm and securing the cap in position. If desired, a rubber or other gasket 12 may 110 be placed between the ring 11 and cap 9. The cap 9 serves to a substantial extent to

cut out or exclude from the diaphragm 5 the ship's noises, and as the button 7 is between the cap and the diaphragm, the sounds transmitted by said button are substantially exclusive of the ship's noises, etc.

The instrument may be positioned or secured against the ship's side in any suitable manner. Herein for the purpose I have shown a casting 13 having lugs 14-14 to engage the angle irons 3-3 and a bolt 15 to secure it in position. A bolt 16 is threaded through the casting 13 at a suitable point and engages the cap 9, as for example in the socket 17. A check nut 18 is provided to hold the bolt in clamping position.

It is apparent that the instrument shown may be placed in any part of the ship below the water line so as to receive the sound vibrations in the manner described, it being unnecessary that it be surrounded with water as heretofore customary.

The plate 5 is secured at its edge to vibrate as a diaphragm. It will be observed that the plate 5 is clamped or secured at its nodal line. The plate is tuned to approximate the pitch of the sound to be received by forming said plate of the proper thickness. By fastening the plate at its nodal line, the pitch to which the plate is tuned is not impaired. In this manner, the plate is therefore a sound selective diaphragm. If, for example, the note of the bell which it is desired the plate shall vibrate to is caused by 1200 vibrations per second, an untuned plate would vibrate to sounds ranging from perhaps 1050 to 1350. By forming the plate of the proper thickness and mounting it at the edge, it is caused to vibrate as a diaphragm and substantially all sounds excepting that of the bell with which it is tuned are excluded. In other words, the diaphragm is very responsive to the bell with which it is tuned, this being indicated by the piercing musical note emitted by the telephonic or microphonic receiver when placed to the ear, other tones above or below such note being dull and without ring. In this manner, noises in the ship, the sound of the washing of the waves and other sounds not of the number of vibrations of the bell referred to, are excluded.

In certain types of vessels, as for example those used upon the Great Lakes, water is employed as ballast. In such cases the instrument may be placed in the water so utilized, and such use of my invention is indicated in Figs. 3 and 4, wherein the instruments are represented as positioned against the skin of the ship at opposite sides at 19, 20. In order to prevent transmission of sound vibrations from one of the instruments to the other, I interpose a suitable screen or screens constructed of a suitable number of layers of material having different sound refracting power. By employing

alternate layers of wood and cement, I have ascertained that a total refraction of the sound received by an instrument is secured so that one instrument does not interfere with another. In said Figs. 3 and 4, I have represented layers 21 of wood with alternate layers 22 of cement. Preferably one or both of the layers taper, such construction serving further to break up the sound waves. Herein the cement layers are represented as alternately tapering in opposite directions. It is, of course, apparent that any suitable substances, preferably solids having differing sound refracting properties, may be utilized. Preferably the sound screens shown in Figs. 3 and 4 are built permanently into the ship, as for example between the adjacent partitions provided in such type of vessel and extending for example from the cross brace 23 to the ship's bottom. Preferably such a screen is provided adjacent each instrument.

It will be apparent from the foregoing description that my invention presents an instrument complete in itself and adapted to be readily secured in position and that it will occupy but little space. The employment of a transmitting medium that may be secured to the face of the vibrator diaphragm and thus position between it and the side of the ship renders the instrument compact and simple.

Having thus described one illustrative embodiment of my invention, I desire it to be understood that although specific terms are employed, they are used in a generic and descriptive sense and not for purposes of limitation, the scope of the invention being set forth in the following claims.

Claims:

1. An instrument for receiving and transmitting submarine signals comprising a vibrator diaphragm, a rubber layer secured against a face thereof, and electric signaling means operatively related to said diaphragm. 105
2. An instrument for receiving and transmitting sub-marine signals comprising a sound selective tuned diaphragm, a rubber layer secured against the face thereof, and signaling means operatively related to said diaphragm. 110
3. An instrument for receiving and transmitting submarine signals comprising a vibrator diaphragm, a rubber layer secured against a face thereof, electric signaling means operatively related to the other face of said diaphragm, and means to secure said instrument in position against the skin of a ship. 120
4. An instrument for receiving and transmitting sub-marine signals comprising a vibrator diaphragm, a rubber layer applied flatwise to one face thereof, signaling means operatively related to said vibrator to convey vibrations received by said diaphragm, 125
- 65

and means to secure said diaphragm flatwise against the skin of a ship with the rubber layer interposed between said diaphragm and the ship's skin.

5. An instrument for receiving and transmitting submarine signals comprising a vibrator diaphragm, a rubber layer positioned flatwise against a face thereof, and signaling means operatively related to said diaphragm to convey vibrations received by said diaphragm.

6. An instrument for receiving and transmitting submarine signals comprising a sound receiving element including a relatively thin, plate like vibrator diaphragm adapted to respond vibratively to sound signals transmitted thereto through water, means to secure said element fixedly flatwise in contact with the usual and unaltered skin 20 of a ship, and an electric signaling means applied directly to and contacting with said element to convey vibrations received by said diaphragm, whereby sound reaching the skin of a ship may be transmitted to the 25 user of the instrument directly through said element and electric signaling means.

7. An instrument for receiving and transmitting submarine signals comprising a sound receiving element including a relatively thin, metallic plate constituting a vibrator diaphragm, said plate being adapted to respond vibratively to sound signals transmitted thereto through water, means to fix said element flatwise in direct contact 30 with the usual and unaltered skin of a ship, and an electric transmitter applied directly to and contacting with said element to convey vibrations received by said element, whereby sounds reaching the skin of a ship 40 may be transmitted to the user of the instrument directly through said element and electric signaling means.

8. An instrument for receiving and transmitting submarine signals comprising a relatively thin, plate-like, vibrator diaphragm adapted to respond vibratively to sound signals transmitted thereto through water, a sound transmitting, flat-facing applied flatwise to one face of said vibrator diaphragm, 45 means to secure said diaphragm fixedly flatwise against the usual and unaltered skin of a ship with said facing between the ship's skin and the diaphragm, and signaling means operatively related to said diaphragm 50 to convey vibrations received by said diaphragm.

9. An instrument for receiving and transmitting submarine signals comprising a relatively thin, plate-like, vibrator diaphragm adapted to respond vibratively to signals transmitted thereto through water, a flexible, sound transmitting layer of stable form applied flatwise to one face of said vibrator diaphragm, means to secure said 55 diaphragm fixedly flatwise against the usual

and unaltered skin of a ship with said layer interposed between the ship's skin and said diaphragm, and electric signaling means operatively related to said diaphragm to convey vibrations received by said diaphragm. 70

10. Means for receiving and transmitting submarine signals comprising a sound receiving element including a relatively thin, plate like vibrator diaphragm adapted to respond vibratively to sound signals transmitted thereto through water, means to fix said element in direct contact with the usual and unaltered skin of a ship, electric signaling means applied directly to and contacting with said element to convey vibrations received by said element and a sound screen distinct from said element but interposed between the same and the ship's interior for the purpose stated. 75

11. Means for receiving and transmitting sub-marine signals comprising a sound receiving element including a relatively thin, plate like vibrator diaphragm adapted to respond vibratively to sound signals transmitted thereto through water, means to fix 80 said element flatwise against the usual and unaltered skin of a ship, electric signaling means applied directly to said diaphragm to convey vibrations received by said diaphragm, and a sound screen distinct from 85 said element and composed of alternate layers of wood and cement, said screen being interposed between the said element and the ship's interior for the purpose stated. 90

12. A sound selective instrument for receiving and transmitting sub-marine signals comprising at least three layers of solid material adjoining flatwise and constituting a single sound selective body, one of said layers being the skin of the ship, and signaling means directly attached to one of 100 said layers. 105

13. A sound selective instrument for receiving and transmitting sub-marine signals comprising at least three face-contacting 110 layers of solid material, one at least of said layers being sound selective, and one of said layers being the skin of the ship, and electric signaling means directly attached to one of 115 said layers.

14. An instrument for receiving and transmitting sub-marine signals comprising a relatively thin, plate-like, vibrator diaphragm adapted to respond vibratively to sound signals transmitted thereto through 120 water, a layer of sound damping material applied to a face of said vibrator diaphragm, means to secure said instrument flatwise against the skin of a ship, and signaling means operatively related to said diaphragm to convey vibrations received by 125 said diaphragm.

15. An instrument for receiving and transmitting sub-marine signals comprising a relatively thin, plate-like vibrator dia- 130

phragm adapted to respond vibratively to sound signals transmitted thereto through water, said diaphragm being adapted to be applied flatwise against the skin of a ship, 5 signaling means operatively applied to the other face of the diaphragm to convey vibrations received thereby, and a cap or inclosure for said other face of the diaphragm.

16. An instrument for receiving and 10 transmitting sub-marine signals comprising a relatively thin, plate-like, vibrator diaphragm adapted to respond vibratively to sound signals transmitted thereto through water, a layer of sound-damping material 15 applied to a face of said vibrator diaphragm, said diaphragm and layer being adapted to be applied flatwise against the skin of a ship, signaling means operatively applied to the other face of the diaphragm 20 to convey vibrations received thereby, and a cap or inclosure for said other face of the diaphragm.

17. An instrument for receiving and transmitting sub-marine signals comprising 25 a relatively thin, plate-like, substantially circular vibrator diaphragm adapted to respond vibratively to sound signals transmitted thereto through water, said diaphragm being adapted to be applied flat- 30 wise to the skin of a ship, a diaphragm inclosing cap engaging the opposite face of said diaphragm along substantially its nodal line only, and signaling means between said cap and diaphragm and opera- 35 tively connected to the latter.

18. An instrument for receiving and transmitting sub-marine signals comprising a relatively thin, plate-like substantially circular, vibrator diaphragm adapted to re- 40 spond vibratively to sound signals trans- mitted thereto through water, said dia- phragm being adapted to be applied flat- 45 wise to the skin of a ship, a diaphragm inclosing cap engaging the opposite face of said diaphragm along substantially its nodal line only, means engaging said cap to fix 50 said diaphragm flatwise against the skin of a ship, and signaling means operatively related to said diaphragm to convey vibra- tions received thereby.

19. An instrument for receiving and transmitting sub-marine signals comprising a relatively thin, plate-like, vibrator dia- phragm adapted to respond vibratively to 55 sound signals transmitted thereto through water, a non-metallic, sound transmitting, flat facing applied flatwise to one face of said vibrator diaphragm, means to secure said diaphragm fixedly flatwise against the

usual and unaltered skin of a ship with said 60 facing between said ship's skin and the dia- phragm, and signaling means operatively related to said diaphragm to convey vibra- tions received by said diaphragm.

20. An instrument for receiving and 65 transmitting sub-marine signals comprising a relatively thin, plate-like, vibrator dia- phragm adapted to respond vibratively to sound signals transmitted thereto through 70 water, a sound transmitting flat facing applied flatwise to one face of said vibrator diaphragm, said facing being of a substance permitting said vibrative response of said diaphragm, means to secure said diaphragm fixedly flatwise against the usual and un- 75 altered skin of a ship with said facing be- tween the ship's skin and the diaphragm, said securing means permitting vibrative re- sponse of said diaphragm, and signaling 80 means operatively related to said dia- phragm to convey vibrations received by said diaphragm.

21. An instrument for receiving and transmitting sub-marine signals comprising 85 a relatively thin, substantially circular, plate-like, vibrator diaphragm adapted to respond vibratively to sound signals trans- mitted thereto through water, a sound trans- 90 mitting, flat facing applied flatwise to one face of said vibrator diaphragm and of a substance permitting said vibrations of said dia- phragm, means engaging said diaphragm along substantially its nodal line only and 95 securing it fixedly flatwise against the usual and unaltered skin of a ship with said fac- 99 ing between the ship's skin and diaphragm, and signaling means operatively related to said diaphragm to convey vibrations re- 100 ceived by said diaphragm.

22. In a submarine sound detection and 10 transmission apparatus the combination 105 with a microphonic detector and a sound conductor consisting of a plate-like vibrator diaphragm, of a sound conductive path in- terposed between the conductor and the body to be tested, said path including a solid plate-like body contacting flatwise with said diaphragm and suitably proportioned to exclude extraneous noises in greater proportion than the sound vibra- 110 tions from the submarine sound source.

In testimony whereof, I have signed my name to this specification, in the presence of two subscribing witnesses.

FORREST E. HOWES.
